UNITED STATES PATENT OFFICE.

KATE DUVAL HUGHES, OF WASHINGTON, DISTRICT OF COLUMBIA.

SASH-FASTENER.

SPECIFICATION forming part of Letters Patent No. 376,654, dated January 17, 1883.

Application filed September 15, 1887. Serial No. 249,885. (No model.)

To all whom it may concern:

Be it known that I, KATE DUVAL HUGHES, a citizen of the United States, residing in the city of Washington, in the District of Columbia, have invented a new and useful Combined Window-Sash Fastener and Holder, of which the following is a specification.

It is the object of the present invention to provide means by which the upper and lower sash of windows may be respectively lowered and raised to a limited extent and secured from further opening from the outside, thus preventing unauthorized persons from gaining ingress by increasing the size of the opening either at the top or bottom of the sash.

In the drawings, Figure 1 represents the window in vertical section, the sash being also shown in section with one form of my locking device. Figs. 2 and 3 represent details. Figs. 20 4 and 5 represents modifications of these details. Fig. 6 represents another arrangement of the locking-chain, differing slightly in connection with that shown in Fig. 1.

In the drawings, A represents the frame of the window, and B represents the sash. These sash may be of ordinary construction, and may be provided with weights or without them, it being understood that my attachment will be made complete in itself and may be applied 30 by every householder.

As shown in Fig. 1, I attach to the window-frame upon the inside a staple, a, which may be attached by means of a plate and screws, as shown in Fig. 2, or by a screw-shank, as 35 shown in Fig. 4. I preferably secure this staple at a point below the meeting line of the sashes, for a purpose hereinafter set forth.

To the upper end of the lower sash, upon one side, I attach a hook, b, which may have a 40 fastening plate, such as that shown in Fig. 3, or a screw-shank, such as shown in Fig. 5, and between the staple a and the hook b, I connect a section of chain, e. This chain, which is to be made with open links, may be of any 45 convenient length, and, as it is connected by means of a hook at one end, it will be understood that any length of the chain may be used by connecting it at any intermediate link with the hook upon the sash, and the 50 window may be raised to a height corresponding to the length of the chain and the position of the staple a. When the lower sash is

thus raised, as shown in Fig. 1, it will be seen that the section of chain e will allow no further movement in an upward position, practically locking the sash so far as upward movement is concerned, while permitting it to be freely closed. In ordinary cases the friction of the sash will hold it in a raised position against the sides of the frame, or when used 55 with weighted sash the weights will keep it in this position. When the lower sash is lowered, the section of chain e can be detached from the hook b at its end link, and the coupling may be made short enough to lock the 60 sash in a closed position.

The upper sash is provided with a like hook, b', which may be attached in either of the ways described, and the section of chain e' extends from the staple a to this hook, crossing over the top of the lower sash. When the upper sash is lowered to the limit of its chain or the limit of any link, it may be connected 70 with the hook upon said sash, and it cannot be further lowered without detaching the 75 chain upon the inside or changing the connection, and it is thus securely locked from further downward movement, though being free to move upward. In order to prevent any wear to the upper part of the sash, a piece of 80 felt or other material may be placed beneath the chain.

In Fig. 6 I have shown a single chain instead of the two sections, one end being connected with the staple a, and an intermediate 85 link being connected with the hook of the lower sash, and one of the end links being fastened to a hook on the upper sash, this being an equivalent arrangement of one chain being provided in place of two.

90 I claim as my invention—

In a window-sash fastener, the combination of a staple, attached to the frame below the meeting-rails of the sashes, a chain secured to the staple, and a scroll-shaped hook attached 95 to the sash, said chain having open links and being capable of attachment to the hook by means of its various links, substantially as described.

KATE DUVAL HUGHES.
